GARMENT HANGER

James H. Russell, St. Louis, Mo., assignor, by
mesne assignments, to Anthony De Luca, St.
Louis, Mo.

Application July 18, 1941, Serial No. 402,907

1 Claim. (Cl. 223—88)

This invention relates to certain new and useful improvements in garment hangers and, more particularly, to a garment hanger adapted for suspending skirts and trousers in fully extended position and without creasing.

My invention has for its primary objects the provision of a combination hanger of the type stated which, in addition to supporting a suit-coat, shirt, or other type of outer garment, will also support either a woman's skirt or a pair of man's trousers in a simple, unique manner, permitting the free circulation of air through the garment for effecting removal of any residual perspiration or body odors remaining within the fibers of the garment after the same has been worn, which will hold the skirt or trousers in smooth shape-retaining condition, freely suspending the garment to prevent wrinkling thereof, which may be readily operated by a single hand, which may be simply and economically constructed, which is rigid and durable, which is capable of almost universal adjustment for skirts and trousers of different sizes, and which is highly efficient in the performance of its stated functions.

And with the above and other objects in view, my invention resides in the novel features of form, construction, arrangement, and combination of parts presently described and pointed out in the claims.

In the accompanying drawings (two sheets)—

Figure 1 is a perspective view of a garment hanger constructed in accordance with and embodying my present invention;

Figure 2 is an enlarged elevational view, partly broken away and in section, of the garment hanger;

Figures 3 and 4 are fragmentary transverse sectional views of the garment hanger taken along the lines 3—3 and 4—4, respectively, Figure 2;

Figure 5 is a perspective view of a slide member of the garment hanger;

Figure 6 is a perspective view of an auxiliary extension-member for use in conjunction with the garment hanger;

Figure 7 is an elevational view of the garment hanger fitted with the extension-members of Figure 6;

Figure 8 is a horizontal sectional view of the garment hanger taken approximately along the line 8—8, Figure 7, illustrating in more detail the manner of operation of the extension-members;

Figure 9 is a perspective view of a modified form of garment hanger constructed in accordance with my present invention;

Figure 10 is an enlarged elevational view, partly broken away and in section, of the modified garment hanger;

Figure 11 is a transverse sectional view of

the modified garment hanger taken approximately along the line 11—11, Figure 10; and

Figure 12 is an elevational view of the modified garment hanger showing the skirt-supporting members thereof in retracted position.

Referring now in more detail and by reference characters to the drawings, which illustrate practical embodiments of the present invention, the garment hanger A includes a bow-member 1 preferably constructed of a shallow concave channel-shaped metallic strip rolled along its longitudinal margins in the provision of lengthwise extending cylindrical beads 2.

Rotatably swiveled in, and presented upwardly from the center of, the bow-member 1, is a conventional suspension-hook 3, and equidistantly on opposite sides of the hook 3, the bow-member 1 is provided with inwardly bent indentations 4 for neatly engaging the neck of a suit-coat and also for retaining the slender silken shoulder straps of a woman's princess slip or evening gown, should the hanger be used for such purpose.

At each end, the bow-member 1 is provided with a pair of L-shaped connectors 5 each having one leg 6 press-fitted into the open end of one of the beads 2 and another leg 7 similarly tightly engaged in the inwardly turned slide-away forming lateral grooves 8 of a channel-shaped transverse bar 9 having a central web 10, in turn, provided at its opposite ends with longitudinally aligned slots 11.

Slidably mounted at the opposite ends of the bar 9, are slides 12 each constructed of a section of suitable wire bent upon itself to preferably integrally include a pair of members 13 sized and spaced for slide-forming disposition within the grooves 8 and connected at their one end by an arcuate bight 14. At their opposite end, the members 13 are bent inwardly and downwardly, as at 15, and welded together, as at 16, in the provision of a substantially rigid and strong structure. Below the weld 16, the wire members 13 are bent outwardly away from each other in the provision of depending legs or prongs 17, which, in turn, diverge slightly outwardly from each other and are provided longitudinally upon their garment-engaging face with a row of serrations, as at 18.

Welded or otherwise secured to, and upstanding through the slot 11 from, the bight 14, is a suitably bent wire finger-grip 19, and hooked at one end around the base portion of the member 19 just above the point of joinder with the bight 14 of a slide 12 and at its other end hooked through a suitably formed aperture in the web 10 of the bar member 9, is a tension spring 20 for normally yieldingly retaining the slide 12 in outwardly shifted position, as shown in full lines in Figure 2.

In use and operation, the finger-grips 19 are

grasped and drawn toward each other, the slides 12 being thereby shifted from the position shown in full lines to the position shown in dotted lines in Figure 2, whereupon the waist-band of a skirt may be draped around the depending prongs 17 and the slides 12 released, drawing the waist-band tightly therearound, as best seen in Figure 1.

It should be noted that, in this supported position, the skirt is held in free-hanging position without creasing or wrinkling and, furthermore, the skirt is held in a more or less open tubular form, so as to permit free circulation of air therethrough for aerating purposes. By reason of the fact that the prongs 17 are inclined outwardly from each other and provided with serrations, as at 18, the hanger A will securely support even the heaviest skirt without difficulty.

When it is desired to employ the hanger for supporting a pair of man's trousers, the slides 12 are drawn toward each other in the manner previously mentioned. One prong of each slide 12 is inserted into the lower end of the leg, so that each cuff will be stretched between the aligned prongs of the two slides. It will thus be evident that the pair of trousers will be held firmly in crease-preserving suspension and the inner portions of the legs will be spaced from each other by a slight distance to allow circulation of air through the crotch of the trousers for airing whenever necessary and, at the same time, preventing any wrinkling or crumpling of the fabric.

Whenever a woman's skirt or a pair of man's trousers is supported by the hanger, a coat, shirt-waist, or other outer apparel garment may be supported at the shoulders over the bow-member 1 of the hanger A in the usual fashion.

By reason of the rather large degree of movement of the slide members 12, the hanger A will readily adjust itself to a wide variety of skirt and trouser sizes. In cases where a skirt of extremely large waist-band or girth must be supported, auxiliary or extension members *a* may be employed, each member *a* being constructed from a sheet metal strip or section having a width substantially equal to the length of the prongs 17 and lengthwise bent into V-shaped formation and curled or rolled at its outer ends in the provision of sockets or channels 21 suitably sized for snug slip-fitting engagement upon the prongs 17 for engaging an out-size skirt, as best seen in Figures 7 and 8.

The modified garment hanger B includes a bow-member 22 formed of wood and contoured in substantially the conventional manner for engaging the shoulder portions of a coat, shirt-waist, or similar apparel garment, and swiveled centrally of the bow-member 22 is a conventional upstanding hook member 23. At its opposite ends, the bow-member 22 is bodily enlarged, as at 22^a, and provided with depending ears 24, which on their inner face merge in a gentle curve 25 into the flattened under or slide face 26 of body-portion 22^a, as best seen in Figures 10 and 12.

Secured by means of conventional wood screws 27 upon each of the slide faces 26, is a tongue 28 suitably elongated for slidable engagement with a bent sheet metal slide channel 29, in turn, mortised into, and by means of wood screws 30 or the like secured to, a shiftable gripper block 31, the blocks 31 being, in turn, contoured for complementally fitting against the inner face of the ears 24 and each projecting outwardly

therefrom in the formation of a somewhat arcuately curved skirt-engaging prong or finger 32.

Fixed at its ends in, and extending longitudinally between, the ears 24 and loosely through the gripper blocks 31 for forming an auxiliary slide or supporting member therefor, is a rod 33, and coiled around the middle portion of the rod 33, is a compression spring 34 fitted snugly within and impinging the end walls of respective shallow sockets 35 formed concentrically around the rod 33 in the adjacent inwardly presented end faces of the gripper blocks 31.

Preferably, though not necessarily, the web portion 29' of the slide-channel 29 is extended beyond the respective inner ends of the gripper blocks 31 and bent upwardly in the formation of finger-grips or hooks 36, all as best seen in Figure 10.

In use and operation, the hooks 36 are manually gripped and drawn toward each other, sliding the gripper blocks 31 inwardly against the bias of the spring 34 from the normal position thereof shown in Figure 10 to the position thereof shown in Figure 12. Thereupon the inwardly drawn skirt-engaging prongs 32 may be inserted into the skirt-band of a woman's skirt and the hooks 36 released, permitting the gripper blocks 31 to yieldingly shift outwardly, under the tension of spring 34, away from each other toward their initial or normal positions, drawing the skirt-band tightly around the prongs 32, as best seen in Figure 9. As soon as the skirt has been mounted upon the hanger, a suit-coat, shirt-waist, or other such outer garment may be placed thereon in the conventional manner.

It should be understood that changes and modifications in the form, construction, arrangement, and combination of the several parts of the hanger may be made and substituted for those herein shown and described without departing from the nature and principle of my invention.

Having thus described my invention, what I claim and desire to secure by Letters Patent is:

In a garment hanger, a bow-shaped member constructed of a channel-shaped strip having its legs presented downwardly, a bar of channel shape in section extending lengthwise between, and at its ends disposed within the channel, and fixed to the ends of said member, said bar having its legs presented downwardly and marginally arcuately bent in the provision of slide-way forming grooves opening inwardly in opposed spaced relation, said bar having a central web provided at its opposite ends with longitudinally aligned slots, slides each constructed of a section of wire bent upon itself and integrally including a pair of strands sized and lengthwise extending in spaced relation and disposed for movement longitudinally within said grooves, said strands being connected at their one end by an arcuate bight and at their opposite end being bent inwardly and downwardly to extend through the open side of the bar and then extended outwardly and downwardly in the provision of a pair of spaced parallel elongated legs for garment engagement, springs lengthwise disposed within the channel of said bar and connected to said slides and to the bar for yieldingly retaining the slides and their said legs in outwardly presented position, and finger-grips fixed to the respective bights of said slides and working in said slots for manipulating the slides against the tension of said springs.

JAMES H. RUSSELL.
